BOTTLE CAPPING MACHINE

Original Filed Aug. 1, 1927

Inventor:

Sigmund L. Goldman,
Bydgoszcz, Poland, Mills,
Attleson

UNITED STATES PATENT OFFICE.

SIGMUND L. GOLDMAN, OF CHICAGO, ILLINOIS, ASSIGNOR TO RED SUN PRODUCTS CO.,
OF CHICAGO, ILLINOIS, A CORPORATION OF ILLINOIS.

BOTTLE-CAPPING MACHINE.

Original application filed August 1, 1927, Serial No. 209,708. Divided and this application filed January 18, 1928. Serial No. 247,622.

My invention relates, more particularly, to bottle-capping machines comprising an upright having a base and carrying a capping-head, and means on the head engaging the upright and by which the desired cap-applying pressure is exerted against a cap applied to a bottle positioned on the base. 5

My primary object is, generally stated, to provide a novel, simple and inexpensive arrangement of parts operative to effect the automatic lifting of the capping head to normal position after release by the operator of the means for forcing the capping-head to cap-securing position. 10

Referring to the accompanying drawing: 15

Figure 1 is a side view of the machine. Figure 2 is a plan sectional view taken at the line 2 on Fig. 3 and viewed in the direction 20 of the arrow. Figure 3 is a detailed view of the capping head of the machine, this view being taken at the line 3-3 on Fig. 2 and viewed in the direction of the arrows. Figure 4 is a section taken at the line 4 on Fig. 3 25 and viewed in the direction of the arrow; and Figure 5, a view in edge elevation taken at the line 5 on Fig. 3 and viewed in the direction of the arrow.

The construction of capping mechanism illustrated comprises generally a base 6, an upright 7 secured to and rising from the base 6 adjacent an edge thereof, a capping head 8 30 slideable up and down on the upright 7 and means for actuating the head 8.

The upright 7 is shown as formed of two bars 9 having straight upper portions 10 at which they fit flatwise together and are riveted in position as represented at 11. The lower ends of the bars 9 are deflected downwardly 35 and outwardly relative to each other, and therefore convergent.

The body of the capping head 8 is preferably formed of a single sheet of metal bent into general U-shape to present substantially 40 parallel spaced apart plate portions 12 at which the head straddles the upper portion of the upright 10, these plate portions being riveted together at 13. The cap-engaging die-portion of the head 8, which may be of 45 any desirable form such, for example, as commonly provided in machines for this purpose, is represented at 14 and is rigidly connected to the plate portions 12 by outwardly bent

lugs 12^a on the bottom edge portions of these plate-portions. 55

The means for actuating the capping head 8 comprise a rack 15 on the upper bar-portion of the upright 10, this rack, in the particular construction shown, being formed by cutting teeth in the adjacent edges of the straight 60 portions of the bars forming the upright. The rack is provided for cooperation with the segmental gear portion 16 of a lever 17 which is located between the plate portions 12 and is fulcrumed on a pin 18 carried by these plate 65 portions and so positioned as to cause the lever to mesh at its gear-portion with the rack 15. The lever is so formed as shown that when it is swung to uppermost position, generally 70 parallel with the upright, the gear portion 16 is disengaged from the rack 15 and the capping head with the parts carried thereby may be freely adjusted along the rack to any desired position of initial engagement of the gear with the rack for bottles of different 75 heights, or, if desired, may be lifted free of the upright to disengage the head from the upright, this being especially desirable where it is desired to reverse the position of the head on the upright, in which position the lever 80 depends, as for example to economize in the space occupied by the machine which is an important factor especially in shipping.

The arrangement of the parts is such that in the initial engagement of the gear with the 85 rack the lever 17 extends in an upward direction and the capping pressure applied to a cap on a bottle positioned on the base 6, is exerted by swinging the lever outwardly and downwardly, the head 8 in this operation 90 descending.

To provide for the normal positioning of the head 8 and lever 17 in raised position with the die-portion 14 clear of the bottle and the return of these parts to such position after 95 the capping operation, I provide a coil spring 19 which is located between the plate-portions 12 at the open side of the head, one end of this spring being releasably connected with the head by a split pin 20 extending through the 100 plate portions 12 and through an eye 21 on the spring and its other end being connected, by an eye 22 thereon, with the lever 17 as shown, these parts being so arranged that in the rocking of the lever 17 to depress the capping head the spring 19 is placed under suf- 105

ficient tension to throw the lever 17 upward and raise the head 8 and lever when the operator discontinues downward pressure thereon.

5 The spring 19 is somewhat wider than the lever 19 and to permit of the free operation of the spring I preferably outwardly deflect those portions of the plate-portions 12 adjacent to which the spring extends, as represented at 23, and as a convenient and simple means of forming a stop for the lever 17 in its downward swinging movement, I indent the edges of the plate portions 12 as represented at 24.

15 It will be understood from the foregoing description that a machine embodying my improvements is not only of simple and inexpensive construction but is rugged and highly resistant to the stresses imposed on it 20 in use. Furthermore, the machine comprises the minimum number of parts and adapts itself to replacements, in case of impairment of parts with quick facility, it being noted that the spring 19 by being located as shown 25 and described, does not require for its attachment the use of a separate plate or bracket on the head and by being secured in place in accordance with the showing may be readily removed and substitution of another therefor 30 quickly and easily effected.

While I have illustrated and described a particular embodiment of my invention, I do not wish to be understood as intending to limit it thereto as the same may be variously 35 modified and altered without departing from the spirit of my invention.

What I claim as new, and desire to secure by Letters Patent, is:

1. A capping machine comprising an up- 40 right, a capping head slideable along said up-right and presenting spaced-apart plate portions, means located between said plate portions for lowering said head on said up-right and a spring located between said plate portions and extending to one side of said up-right and engaging said means and head for returning said head to raised position.

2. A capping machine comprising an up- 50 right, a capping head slideable along said up-right and presenting spaced-apart plate portions, means located between said plate portions for lowering said head on said up-right and a spring located between said plate portions and extending to one side of said up-right and engaging said means and head for

returning said head to raised position, said plate portions having outwardly deflected portions to accommodate said spring.

3. A capping machine comprising an up- 60 right, a capping head slideable along said up-right and presenting spaced-apart plate portions, lever means located between said plate portions for lowering said head on said up-right and a spring located between said plate portions and arranged to co-act with said 65 lever and said plate-portions for returning said means to raised position.

4. A capping machine comprising an up- 70 right, a capping head slideable along said up-right and presenting spaced-apart plate portions, means located between said plate portions for lowering said head on said up-right and a spring located between said plate portions and connected at its opposite ends to 75 said plate portions and to said means for returning said head to raised position.

5. A capping machine comprising an up- 80 right, a capping head slideable along said up-right and presenting spaced-apart plate portions, lever means located between said plate portions for lowering said head on said up-right and a spring located between said plate portions and connected at its opposite ends to 85 said plate portions and to said means for returning said head to raised position.

6. A capping machine comprising a rack- 90 equipped up-right, a capping head slideable along said up-right and presenting spaced-apart side portions, means, comprising a toothed element engaging said rack, located between said plate portions for lowering said head on said up-right, and a spring located between said plate portions and extending to one side of said up-right and engaging said 95 means and head for returning said head to raised position.

7. A capping machine comprising a rack- 100 equipped up-right, a capping head slideable along said up-right and presenting spaced-apart side portions, means, comprising a toothed element engaging said rack, located between said plate portions for lowering said head on said up-right, and a spring located between said plate portions and extending to one side of said up-right and engaging said 105 means and head for returning said head to raised position, said plate portions having outwardly deflected portions to accommodate said spring.

SIGMUND L. GOLDMAN.
